UNITED STATES PATENT OFFICE.

EDWARD C. HOFFMANN, OF SCRIBNER, NEBRASKA.

DESIGN FOR A REINFORCED KETTLE.

43,106.

Specification for Design.

Patented Oct. 8, 1912.

Application filed March 18, 1912. Serial No. 684,627. Term of patent 14 years.

To all whom it may concern:

Be it known that I, EDWARD C. HOFFMANN, a citizen of the United States, and a resident of Scribner, in the county of Dodge and State of Nebraska, have invented a new, original, and ornamental Design for a Reinforced Kettle.

Reference is to be had to the accompanying drawing, in which the figure is a per-

spective view of a reinforced kettle showing my design.

I claim:

The ornamental design for a reinforced kettle, as shown.

EDWARD C. HOFFMANN.

Witnesses:

E. R. COOK,
A. B. LAKE.
